CIRCUIT INTERRUPTER

Benjamin P. Baker, Turtle Creek, Pa., and Oswald von Mehren, Lorain, Ohio, assignors to Westinghouse Electric Corporation, East Pittsburgh, Pa., a corporation of Pennsylvania

Application November 23, 1945, Serial No. 630,350

16 Claims. (Cl. 200—82)

1

This invention relates to circuit interrupters in general and more particularly to operating mechanisms therefor. More specifically, our invention relates to an improved operating mechanism for a compressed gas circuit interrupter of the pressurized chamber type.

Certain aspects of the invention apply in particular to a circuit interrupter of the gas blast type utilizing a pressurized chamber into which extends a pair of terminal bushings of the type ordinarily used in oil breakers. The gas contained within the pressurized chamber is partly used to obtain high dielectric strength within the region enclosed by the chamber, and is also partly used to effect the extinction of the arc drawn in the pressurized chamber by utilizing a suitable arc extinguishing device in conjunction with the gas blast. Preferably, the gas blast, utilized to effect arc extinction, passes out of the pressurized chamber through the terminal bushing itself.

In U. S. patent application, Serial No. 565,456, filed November 28, 1944, now Patent No. 2,507,210, issued May 9, 1950, entitled "Circuit Interrupters" by Leon R. Ludwig and Benjamin P. Baker and assigned to the assignee of the instant application a number of features of the invention are disclosed and claimed.

It is an object of our invention to provide an improved operating mechanism for a circuit interrupter of the foregoing type.

The provision of a suitable operating mechanism adaptable for use in a circuit interrupter of the type disclosed in the foregoing application is rendered difficult in attainment inasmuch as the pole unit mechanism must be capable of providing a long travel inside of the pressure enclosure or tank and preferably a short motion of the member transmitting the motion from the outside to the inside without leakage of the pressure gas, and with means for registering accurately the final closed position for electrical control purposes.

Another object of our invention is to provide an improved operating mechanism for actuating contact means including an operating rod having secured thereto a piston movable in an operating cylinder. Preferably, we employ holding means for holding the operating rod in the closed circuit position and releasing means to effect release of the holding means. By the construction which we employ the releasing means has a relatively short travel as compared to the relatively long travel of the operating rod.

Another object is to provide an improved operating mechanism of the type described in the preceding paragraph in which second holding

5

means are employed to effect holding of the releasing means. Preferably, tripping of the second holding means automatically by an interlocking construction, prevents closing operation of the interrupter.

10

Another object is to provide an improved operating mechanism suitable for use in a circuit interrupter in which interlocking means are provided between the opening and closing mechanism so that opening takes precedence over the closing operation. Preferably, we accomplish such a result by utilizing an exhaust valve associated with the closing valve mechanism which is operated by the electric means used to trip the breaker.

15

Another object is to provide an improved operating mechanism for a circuit interrupter in which the operating mechanism is supplied with gas from a pressure chamber about the interrupter.

20

Another object is to provide an improved circuit interrupter in which only one air inlet to the entire interrupter is required.

25

Another object is to provide an improved high speed mechanism for a circuit interrupter in which high speed opening is obtained because of unlatching at the top of the lift rod and in which the moving parts have a relatively small mass.

30

Further objects relate to details of construction which will be more apparent hereinafter upon reading the specification taken in conjunction with the drawings, in which:

35

Figure 1 shows a side elevational view partly in section of a gas blast type of circuit interrupter of the pressurized tank construction embodying our invention and shown in the closed-circuit position;

40

Fig. 2 is an enlarged vertical sectional view through a portion of the operating mechanism for the breaker shown in Fig. 1;

45

Fig. 3 is a sectional view taken along the line III—III of Fig. 2;

50

Fig. 4 is a sectional view taken along the line IV—IV of Fig. 2; and

55

Fig. 5 is a diagrammatic view of the electrical control circuit for the interrupter.

Referring to the drawings, and more particularly to Fig. 1 thereof, the reference numeral 1 designates an enclosure of spherical shape forming a pressurized chamber. Secured as by welding to the lower end of the pressurized chamber is a plurality of, in this instance four, base supports 2. Extending from the upper end of the enclosure 1 are hollow terminal bushings 3, 4 through which extend respectively exhaust passages 3a, 4a and which support, respectively, at

2

their upper ends line terminals 5, 6. A high pressure gas inlet conduit 5a leads into tank 1 from a suitable source, not shown, of high pressure gas.

Secured to the lower ends of the terminal bushings 3, 4 are two serially related arc extinguishing units generally designated by the reference numeral 7. These units 7 and other parts of the device disclosed herein have a construction more specifically set forth and claimed in U. S. patent application, Serial No. 624,284, filed October 24, 1945, by Benjamin P. Baker and Oswald von Mehren and assigned to the assignee of the instant application.

Electrically interconnecting the two arc extinguishing units 7 in the closed-circuit position as shown in Fig. 1, is a conducting cross-bar or bridging member 8 which in the fully open-circuit position of the interrupter assumes a position indicated by the dotted lines 9.

The conducting cross-bar 8 is reciprocally operated in a vertical direction by an insulating operating rod 10 which is preferably guided within a bushing 11, the latter being secured by brackets 12 and bolts 13 to the upper wall 14 of the enclosure 1. Positioned on top of the enclosure 1 is the operating mechanism for the interrupter generally designated by the reference numeral 15 and contained within a metallic housing 16.

An operating cylinder 17 has its lower end welded as at 18 to the wall 14 of the container 1. High pressure gas which is present within the region 19 in the interior of the container 1 communicates with the space 20 (Fig. 2) below the piston 21 by means of the operating cylinder 17. Consequently, high pressure gas within the tank 1 tends to force the piston 21 secured to the upper end of the lift rod 10 in an upward direction, as viewed in Fig. 1. This use of compressed gas taken from the arc extinguisher enclosure is a distinct advantage in breaker construction since no additional air pipes are required to supply air to the operating mechanism.

The piston 21, coupled to the operating rod 10, and movable within the operating cylinder 17 constitutes a fluid motor generally designated by the reference numeral 22.

The piston 21 has an upstanding rod portion 24 having at its upper end integrally formed therewith a latching head 25, the latter being latched or held in the closed circuit position as shown in Fig. 2 by means of two latch pins 26. The two latch pins 26 and the latch head 25 secured to the upper end of the operating rod 10 collectively form a first releasable or holding means generally designated by the reference numeral 27. Each latch pin 26 has pivotally mounted thereon two links 28, as shown more clearly in Fig. 4 of the drawings. The four links 28 have two pins 30 cooperating therewith at their upper ends, the two pins 30 passing through a member 31. Threadedly secured to the member 31 is a rod 32 externally of which is positioned a Sylphon bellows 34. The Sylphon bellows is secured as by soldering at its upper end to a ring 35, the latter being secured as by screws 36 to a cylindrical member 37 having a flange portion 38. The flange portion 38 is preferably secured as by bolts 40 and nuts 41 to a flange 42. The flange 42 is welded as at 43 to the upper end of a metallic cylinder 44.

A metallic insert 121 is provided being threadedly secured at 122 into the lower end of the cylinder 37. The insert 121 has cam surfaces 123 formed thereon to extend the pins 26 laterally to effect release of the latch head 25 during the

opening operation. Bumper stops 124 are preferably provided to take the shock during the closing operation.

Welded at 45 adjacent the lower end of the cylinder 44 is a ring-shaped casting member 46. Welded to the lower end of the casting member 46 as at 47 is the operating cylinder 17.

Biassing means are employed to bias the piston 21 and operating rod 10 to the open-circuit position, in this instance consisting of a compression spring 49 disposed in the interior of the cylinder 44, having its lower end resting upon the piston 21 and having its upper end in abutting engagement with the flange 38. The rod 32 has its upper end 50 threaded and cooperates with nuts 51 and 52 to rigidly secure in place a spring plate casting member 53 which is biased downwardly by a battery of compression springs, in this instance comprising the two coacting compression springs 54, 55. The springs 54, 55 are positioned within a housing 56 having at its lower end a flange portion 57 which is maintained in position by the bolts 40 and nuts 41.

Integrally formed with the housing 56 are two upstanding support plates 58 more clearly shown in Fig. 3, and only one of which is shown in Fig. 2. A pin 59 extends through the upper ends of the support plates 58 and pivotally mounts a second releasable or holding means generally designated by the reference numeral 60 and in this instance including a latched plate 61. The latch plate 61 is pivotally mounted on the pin 59 and has a notched portion 62 provided adjacent its lower end which serves to latch a hold in the closed-circuit position as shown in Fig. 2 a roller 63 pivotally mounted on a pin 64, the latter in turn extending through two legs 65 preferably integrally formed with the casting plate 53.

40 A latch trigger 66 is pivotally supported on a pin 67, the latter extending through both support plates 58. A tripping electromagnet generally designated by the reference numeral 68 is provided consisting of a solenoid 69 which serves to actuate when energized an armature 70, causing the latter to move a push rod 71 upwardly into engagement with an adjustable stop 72 secured to the right-hand end of the latch trigger 66.

50 A compression spring 73 is provided to bias the latch trigger 66 in a clockwise direction, as viewed in Fig. 2, about the pin 67. The lower end of the compression spring 73 abuts against a portion 74 integrally formed with the housing 56.

55 An auxiliary switch generally designated by the reference numeral 78 is employed to actuate control contacts and to indicate the open and closed positions of the mechanism. Preferably, the auxiliary switch 78 is actuated by a bell crank 79 pivotally mounted on a pin 80 and having two leaf springs 81, 82 secured thereto. Positioned between the leaf springs 81, 82 is a pin 83 secured to the left-hand end of an indicating lever 84, the latter being pivotally mounted adjacent its right-hand end on a pin 85 extending through one of the support plates 58.

60 A closing electromagnet generally designated by the reference numeral 89 is provided to effect a closing operation of the interrupter. The closing electromagnet 89 when energized actuates a pilot valve 90. The pilot valve 90 controls the flow of high pressure gas from the tank 1 through a high pressure conduit 91 by valve means generally designated by the reference numeral 92. 70 The valve means comprises a valve member 93

which is of the double acting type and controls the flow of gas in through an inlet port 94 and out through an exhaust port 95. The valve member 93 has a valve stem 96 secured thereto. Secured to the valve stem 96 is a piston 97 biased upwardly by a compression spring 98. Thus, the compression spring 98 serves to bias the valve means 92 to the position shown in Fig. 2. A nut 99 threadedly secured to the upper end of the valve stem 96 serves to hold the piston 97 rigidly in place to the valve stem 96.

The valve stem 96 has its upper end bored to guidably receive a stem 102, the upper end of which is secured to a dump valve 103 controlling an exhaust port 101. The upper end of the dump valve 103 is extended to be rigidly connected to a rod 104, the upper end of which is pivotally connected by means of a pin 105 to the right-hand end of a lever 106. The lever 106 pivotally rotates about a fixed pivot consisting of a pin 107, the latter passing through only one of the support plates 58. An aperture 108 is provided in the latched trigger 66 to accommodate the rod 104. A pin 111 passes through the rod 104 and is engaged by two bosses 112 integrally formed with the latched trigger 66. Thus, when the tripping electromagnet 68 is energized to cause counterclockwise rotative movement of the latched trigger 66, and as soon as it has rotated far enough to unlatch member 61, the bosses 112 engage the pin 111 passing through the rod 104 to maintain the dump valve 103 open. The purpose for this arrangement will be more clearly understood by the description given hereinafter.

Provided in the casting member 46 is a passage 115 controlled by the pilot valve 90 and communicating when the pilot valve 90 is open by means of the passage 116 to the space 117 above the piston 97. The space 118 below the piston 97 is in communication with the atmosphere by way of the exhaust ports 119, a plurality of which are provided. A bleeder opening 125 is provided to permit exhausting of air from the space 117 above the piston 97.

It will be observed that the rod 32, casting member 53, springs 54, 55 and cam surfaces 123 collectively form a releasing means generally designated by the reference numeral 126 for the first releasable or holding means 27.

Referring more particularly to Fig. 5 which shows the electrical control circuit for the interrupter, it will be observed that we have provided a protective relay 131 having a winding energized by the current flowing through a winding 132 which is responsive to the flow of current passing through the power line 133 controlled by the interrupter. The control circuit is preferably energized by a source of power which consists of a negative line 134 and a positive line 135 as indicated in Fig. 5. Back contacts 136 of the auxiliary switch 78 control the electrical circuit through a green light 155 which is lighted when the breaker is in the open position, as shown in Fig. 5. Front contacts 137 of the auxiliary switch 78 control the circuit through a red light 154 which is lighted when the breaker is in the closed position, not shown in Fig. 5. The front contacts 138 of the protective relay 131 are in shunt with a trip button 139.

We provide an interlock relay 140 which energizes the closing circuit when the opening circuit is energized. The winding for the interlock relay 140 extends through front contacts 141 of the auxiliary switch 78. The interlock relay 140 has a pair of front contacts 142 which serve

to maintain a shunting circuit about both the trip button 139 and the front contacts 138 of the protective relay 131. Thus, momentary pressing of the trip button 139 or momentary operation of the protective relay 131 will serve to energize the interlock relay 140, closing the front contacts 142 and maintaining a circuit around the trip button 139 or contacts 138 to insure completion of the opening operation. The interlock relay 140 is provided with a pair of back contacts 143 which are in series circuit with the winding through the electromagnet 89.

A closing relay 144 is provided which is energized during the closing operation. The closing relay 144 has a pair of front contacts 145 which are in series with the winding through the electromagnet 89. The closing relay 144 also has another pair of front contacts 146 which provide a shunting circuit about the closing button 153. An anti-pump relay 149 is provided having a pair of back contacts 150 which are in series with the winding through the closing relay 144. The anti-pump relay 149 also has a pair of front contacts 151 which serve to maintain the winding of the anti-pump relay energized following opening of the front contacts 152 of the auxiliary switch 78 during the opening operation to prevent "pumping." This electrical control feature is well known in the art, and a further description thereof appears unnecessary.

The operation of the interrupter will now be explained. In the closed circuit position, as shown in Figs. 1 through 4, the electrical circuit therethrough extends from the line terminal 3 through the terminal bushing 3, left-hand arc extinguishing unit 7, cross-bar 8, right-hand arc extinguishing unit 7 to the right-hand line terminal bushing 4 to the right-hand line terminal 6. To open the breaker, either the trip button 139 is manually operated, or the protective relay 131 is operated by an overload passing through the line 133 to close the front contacts 138. This energizes the windings of the interlocking relay 140 and the tripping electromagnet 68. Back contacts 143 of the interlock relay 140 open to break any circuit through the electromagnet 89, which provides an electrical interlock feature between the opening and closing circuits, thus giving preference to the opening circuit. Also, front contacts 142 of the interlock relay 140 closes to maintain a circuit around the trip button 139 or the front contacts 138 of the protective relay 131, as previously mentioned. This insures completion of the opening operation.

The energizing of the tripping electromagnet 68 effects upward movement of the armature 70 and hence push rod 71. This causes counterclockwise rotative releasing motion of the latch trigger 66 to release the latch plate 61, and sufficient overtravel to permit the bosses 112 to strike the pin 111 to thereby maintain the dump valve 103 open as long as electromagnet 68 is energized.

The latch plate 61 when permitted to move counterclockwise releases the roller 63 to thereby permit the compression springs 54, 55, 49 and the accelerating springs associated with the units 1 to force the releasing means 126 and the operating rod 10 downwardly a distance L as indicated in Fig. 2. The pin 64 passing through the indicating lever 84 actuates the auxiliary switch 78 by clockwise rotation of the bell crank 79. Also, the downward movement of the releasing means 126 causes the latch pins 26 to spread outwardly by virtue of the cam surfaces 123 to ef-

fect release of the latch head 25. Since the valve means 92 is in the position shown in Fig. 2, high pressure gas exists on both sides of the piston 21 and hence the net downward force exerted by the compression spring 49 will force the piston 21 to move downwardly rapidly a considerable distance within the operating cylinder 17 to effect separation of the contact means disposed within the arc extinguishing units 7.

It will be observed that although the operating rod 10 and piston 21 have a considerable length of travel, the releasing means 126 only has the relatively short travel measured by the distance L. The Sylphon bellows 34 is employed to prevent high pressure gas which is adjacent the first latching means 27 during the opening operation from escaping to the low pressure region 23 adjacent the casting plate 53. The Sylphon bellows construction is possible because of the limited downward opening travel of the releasing means 126. The piston 21 moves downwardly free of the first latching or holding means 27, having no engagement therewith until the cross-bar 8 assumes the position 9, as shown in Fig. 1. Thus when the breaker is open, front contacts 141 of auxiliary switch 78 open to break the energizing circuit through the tripping electromagnet 68. The interrupter is now fully open, all of the circuits being deenergized except the circuit passing through the green light 155.

To close the interrupter, the closing button 153 is pressed, even though momentarily. This energizes the winding of the closing relay 144. The front contacts 145 of the closing relay 144 close and hence energize electromagnet 89. Also, the front contacts 146 of the closing relay 144 close and maintain the circuit through the winding of the closing relay 144 around the closing button 153. Thus, momentary closing of the closing button 153 is sufficient.

The energization of the electromagnet 89 causes opening of the pilot valve 90. This permits high pressure gas passing upwardly from the enclosure 1 through the high pressure conduit 91 to pass through the passage 115 past the pilot valve 90 through the passage 116 to the region 117 above the piston 97. At this time it will be observed that the dump valve 103 is closed since the tripping electromagnet 68 is deenergized and compression spring 73 restores the trigger latch clockwise until the latching end thereof rests against the end of the latch 61. This movement is sufficient to permit the bosses 112 to move away from the pin 111. Also, it is to be noted that the compression spring 75 tends to maintain the dump valve 103 closed against the exhaust port 101. Consequently, in view of the above state of affairs, the high pressure gas passing from the conduit 91 into the space 117 and at a greater rate than it is exhausted through the bleeder opening 125 will force the piston 97 downwardly against the force exerted by the compression spring 98 to cause the valve member 93 to close the inlet port 94 and open the exhaust port 95.

This exhausts high pressure gas above the piston 21 through the exhaust port 95 and out 119 into the atmospheric region. The high pressure gas within the tank 1 communicating with the region 20 biases the piston 21 upwardly, and since the upper side of the piston 21 communicates with atmosphere through the exhaust ports 95, 119, the high pressure gas in the region 20 will serve to move rapidly the piston 21 and hence the operating rod 10 upwardly toward the closed circuit position of the interrupter.

Near the end of the closing stroke the latch head 25 strikes the latch pins 26, the latter being biased toward each other by suitable means not shown, to effect latching or holding engagement of the piston 21 and operating rod 10. The continued upward movement of the piston 21 causes the releasing means 126 to move upwardly the relatively short distance L to force the roller 63 upwardly into the notched portion 62 and hence to effect clockwise rotative latching movement of the latch plate 61. The compression spring 73 forces the latch trigger 66 into latching engagement with the latch plate 61, and at the fully closed position of the interrupter, as shown in Fig. 2, the roller 63 strikes the left-hand end 77 of the lever 106 to effect opening of the dump valve 103. The parts then assume the position shown in Fig. 2, and the breaker is fully closed.

Closing of the front contacts 152 of the auxiliary switch 78 in the closed position of the breaker energizes the winding of the anti-pump relay 149 which closes. Opening of the back contacts 150 of the anti-pump relay 149 breaks the energizing circuit through the winding of the closing relay 144. The closing relay 144 hence opens, and the front contacts 146 thereof also open to break the energizing circuit through the winding of the anti-pump relay 149. Also, the front contacts 145 open to break the energizing circuit through the winding of the electromagnet 89. The breaker is now fully closed, all the circuits are deenergized except the electrical circuit passing through the red light 154.

It will be observed that not only is there an electrical interlock circuit provided between the tripping electromagnet 68 and the electromagnet 89 by virtue of the interlock relay 149, but also structurally we provide an interlocking arrangement so as to make the opening operation take precedence over closing operation of the breaker. More specifically, when the tripping electromagnet 68 is energized to cause counterclockwise rotative movement of the latch trigger 66 which effects engagement between the bosses 112 and the pin 111 when it has slightly overtraveled its unlatching position to maintain the dump valve 103 open, should the electromagnet 89 be energized at this time to effect opening of the pilot valve 90, the exhausting of air from the region 117 above the piston 97 through the exhaust port 101 and bleeder opening 125 is greater than the passing of high pressure gas from the passage 115, 116 into the region 117. Consequently, the pressure is maintained sufficiently low in the space 117 so that the compression spring 98 maintains the piston 97 in its raised position, as shown in Fig. 2, to thereby equalize the pressure on the piston 21 and hence to permit accelerating spring 49 to cause opening motion regardless of the state of energization of the electromagnet 89. Thus, we structurally provide an arrangement whereby should both the electromagnet 89 and the tripping electromagnet 68 be energized at the same time, the opening operation would take precedence over the closing operation.

It is to be observed that in the fully closed circuit position of the interrupter, as shown in Fig. 2, the exhaust valve 103 is open. It is forced open since the roller 63 strikes the left-hand end 77 of the lever 106 in the closed circuit position. This has the following advantage. Assume that in the open circuit position of the interrupter a fault condition still exists in the line 133. During the closing operation when the electromagnet 89 is energized, high pressure will exist in the space

117 above the piston 91. When the breaker reaches its fully closed position, it will be tripped open by operation of the protective relay 131. However, even though the tripping electromagnet 68 is energized, the piston 21 will not move downwardly unless the pressure is equalized thereon, that is, high pressure gas exists on the top of the piston 21, as well as on the bottom thereof. Thus, valve member 93 must be in the position shown in Fig. 2 as soon as possible to insure rapid opening of the piston 21 and hence operating rod 10. By opening the dump valve 103 at the extreme end of the closing stroke, should the breaker have been closed on a short circuit, the rapid dumping of air from the space 117 will permit valve member 93 to quickly move to its raised position, as shown in Fig. 2, the dump valve 103 cooperating with the bleeder-opening 125 to rapidly exhaust high pressure gas from the space 117. Thus, by causing the opening of the dump valve 103 at the extreme end of the closing stroke, we provide an operating mechanism which is especially desirable where rapid opening is desired when the breaker is closed on a short circuit.

From the foregoing description, it will be apparent that we have provided an improved operating mechanism for a circuit interrupter of the gas blast type in which a relatively long travel of the lift rod is desired, and where it is not desired to have a relatively long travel of the mechanism used to initiate opening movement of the lift rod. Thus, with the construction illustrated, although the piston 21 travels a considerable distance, the releasing means 126 has only the slight travel L. A Sylphon bellows construction for sealing the opening into the pressure chamber through which the operating mechanism is controlled is therefore possible.

It will be furthermore understood that certain features of the invention are applicable not only to circuit interrupters of the pressurized tank construction but to any type of circuit interrupter in which it is desired to have the operating rod set free after its initiation, and controlled exclusively thereafter by biasing means, such as an accelerating compression spring.

The construction illustrated not only provides rapid opening and closing operations but enables the opening operation to take precedence structurally over the closing operation. Furthermore, the mechanism is adaptable for high speed re-opening when closing the interrupter during the existence of short circuit conditions in the power line 133.

Although we have shown and described a specific structure, it is to be clearly understood that the same was merely for the purpose of illustration and that changes and modifications may readily be made therein by those skilled in the art without departing from the spirit and scope of the appended claims.

We claim as our invention:

1. In a circuit interrupter, contact means for establishing an arc, an operating rod for actuating the contact means, an operating cylinder, a piston secured to the operating rod and movable within the operating cylinder, means for admitting gas pressure to said cylinder on both sides of said piston, means holding the operating rod in the closed-circuit position, means biasing the operating rod to the open-circuit position, and means for equalizing the pressure on both sides of the piston during the opening operation.

2. In a circuit interrupter, means defining a pressurized chamber, contact means for estab-

lishing an arc within the pressurized chamber, an operating rod for actuating the contact means, an operating cylinder, a piston secured to the operating rod and movable within the operating cylinder and one side of said piston being subjected to the pressure in said chamber at all times, means holding the operating rod in the closed circuit position, means biasing the operating rod to the open circuit position, and means for admitting pressure to the other side of the piston to permit opening operation.

3. In a circuit interrupter, a pressurized chamber, a contact operating rod extending into the chamber and movable therein, an operating cylinder, a piston movable within the operating cylinder and secured to one end of the operating rod, means biasing the piston in such a direction so as to move the operating rod into contact opening position, means subjecting both sides of the piston to high pressure gas from the pressurized chamber during the opening operation, and means permitting exhausting of high pressure gas on one side of the piston during the closing operation to permit the high pressure gas within the pressurized chamber to effect closing motion of the piston.

4. In a circuit interrupter, contact means for establishing an arc, operating means for the contact means including an operating rod with a relatively long travel, first releasable means for holding the operating rod in the closed circuit position disposed in a region of high pressure, releasing means for the first releasable means having a relatively short travel, and second holding means for holding the releasing means disposed in a region of relatively low pressure, and a Sylphon bellows movable with the releasing means.

5. In a circuit interrupter, contact means for establishing an arc, an operating rod for actuating the contact means, an operating cylinder having one end communicating with a region of high pressure, a piston secured to the operating rod and movable within the operating cylinder, means defining a passage for admitting high pressure to the other end of said cylinder means biasing the piston in the opening direction, means equalizing the high pressure on both sides of the piston during the opening operation, first holding means for holding the operating rod in the closed position, releasing means for the first holding means, and second holding means for holding the releasing means.

6. In a circuit interrupter, contact means for establishing an arc, an operating rod having a relatively long travel for actuating the contact means, an operating cylinder, a piston secured to the operating rod and movable within the operating cylinder, means for admitting gas pressure to said cylinder on both sides of said piston, means biasing the piston in the opening direction, means equalizing pressure on both sides of the piston during the opening operation, first holding means for holding the operating rod in the closed position, releasing means for the first holding means having a relatively short travel, and second holding means for holding the releasing means.

7. In a circuit interrupter, contact means for establishing an arc, an operating rod having a relatively long travel for actuating the contact means, an operating cylinder, a piston secured to the operating rod and movable within the operating cylinder, means for admitting gas pressure to said cylinder on both sides of said piston, means biasing the piston in the opening direction,

11

means equalizing pressure on both sides of the piston during the opening operation, first holding means for holding the operating rod in the closed position, releasing means for the first holding means having a relatively short travel, second holding means for holding the releasing means, means providing relatively high pressure adjacent the first holding means during the opening operation, means providing relatively low pressure adjacent the second holding means, and Sylphon bellows means movable with the releasing means to prevent intercommunication between the high pressure and low pressure regions.

8. In a circuit interrupter of the gas blast type, contact means separable to draw an arc, a fluid motor including a pressure actuated piston movable axially for actuating the contact means, first holding means for holding said piston in the closed circuit position, means biasing said piston toward the opening direction, releasing means disposed in axial alignment with said piston and movable axially relative to said piston to release the first holding means, means biasing the releasing means in releasing direction, and a second holding means for releasably holding the releasing means.

9. In a circuit interrupter of the gas blast type, contact means separable to draw an arc, a fluid motor including a pressure actuated axially movable member having a relatively long travel for actuating the contact means, first holding means for releasably holding the member in the closed circuit position, means biasing the member toward the opening direction, releasing means disposed in axial alignment with said member to be moved axially relative to said member and having a relatively short travel to release said first holding means, means biasing the releasing means in releasing direction, and second holding means for releasably holding the releasing means.

10. In a circuit interrupter, contact means for establishing an arc, operating means for the contact means including an operating rod with a relatively long travel, first releasable means for holding the operating rod in the closed circuit position disposed in a region of high pressure, releasing means for the first releasable means having a relatively short travel, and second holding means for holding the releasing means disposed in a region of relatively low pressure, and means preventing communication between the high and low pressure regions.

11. In a circuit interrupter, contact means, an operating rod in two separable parts for causing the actuation of the contact means, an automatic disconnect means between the two parts to permit separation of said parts and independent movement of one of the two parts upon movement of the operating rod in the opening direction, restraining means normally restraining said automatic disconnect means, and electro-responsive means operable to effect release of said automatic disconnect means.

12. In a circuit interrupter, a pressure chamber, contact means within the pressure chamber, an operating means in two releasable parts for causing the actuation of the contact means, a releasable connection between the two parts within the pressure chamber, and means for effecting the release of the releasable connection to permit independent movement of one of the two parts upon movement of the operating means in the opening direction.

13. In a circuit interrupter, contact means,

an operating means in two separable parts for causing the actuation of the contact means, a releasable connection between the two separable parts, a piston connected to the operating means between the contact means and the releasable connection, and means for effecting the release of the releasable connection to permit separation of said parts and independent movement the part connected to the contact means upon movement of the other part in the opening direction.

14. In a circuit interrupter, a pressure chamber, contact means within the pressure chamber, an operating means in two releasable parts and extending into the pressure chamber for causing the actuation of the contact means, a releasable connection between the two parts within the pressure chamber, means for effecting the release of the releasable connection to permit independent movement of the part within the pressure chamber upon movement of the part of the operating means outside of the pressure chamber in the opening direction, and a piston within the pressure chamber and secured to the part which moves independently in the opening operation.

15. In a circuit interrupter, contact means, an operating means in two separable parts for causing the actuation of the contact means, a releasable connection between the two parts, means effecting the release of the releasable connection during the initial portion of the opening operation to permit separation of said parts and independent movement of the contact actuating part in the opening direction, holding means for the operating means, and the re-engaging movement of the independently movable part moving the other part during the closing operation to position where it is held by the holding means.

16. A circuit interrupter including separable contact means, operating means for said contact means including an operating rod having a relatively long axial travel to open and close said contact means, a first holding means for releasably holding said operating rod in closed position, releasing means disposed in axial alignment with said operating rod and having a relatively short axial travel relative to said operating rod to actuate said first holding means to thereby release said operating rod, a second holding means for releasably holding said releasing means and operable to effect release of said releasing means, spring means biasing said releasing means in releasing direction and operable upon operation of said second holding means to actuate said releasing means, and an operating piston disposed between said contact means and said first holding means.

BENJAMIN P. BAKER.
